CLAIM

The ornamental design for canopy shelter, as shown and described.

DESCRIPTION

The design is for a canopy shelter to shelter individuals and which may be used as a bus stop shelter or any other type of shelter to provide protection. Such may be provided with integral lighting.

FIG. 1 is a top and right front perspective view of canopy shelter showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.
